UNITED STATES PATENT OFFICE.

DUDLEY FREEMAN, OF ROXBURY, MASSACHUSETTS, ASSIGNOR TO PANTHER RUBBER MANUFACTURING COMPANY, OF STOUGHTON, MASSACHUSETTS, A CORPORATION OF MASSACHUSETTS.

DESIGN FOR A SHOE HEEL.

Application filed March 11, 1922. Serial No. 1,132. Term of patent 14 years.

To all whom it may concern:

Be it known that I, DUDLEY FREEMAN, a citizen of the United States, residing at Roxbury, in the county of Suffolk and Commonwealth of Massachusetts, have invented a new, original, and ornamental Design for a Shoe Heel, of which the following is a specification, reference being had to the ac-

companying drawing forming a part thereof. The figure of the drawing is a plan view of a shoe heel showing my new design.

I claim:

The ornamental design for a shoe heel as shown.

DUDLEY FREEMAN.
